UNITED STATES PATENT OFFICE.

JAMES E. BUSHNELL, OF COLD SPRINGS, NEW YORK, ASSIGNOR TO HYATT ROLLER BEARING COMPANY, OF HARRISON, NEW JERSEY, A CORPORATION OF NEW JERSEY.

CAR-AXLE MOUNTING.

1,358,056.

Specification of Letters Patent.

Patented Nov. 9, 1920.

Application filed May 19, 1920. Serial No. 382,648.

To all whom it may concern:

Be it known that I, JAMES E. BUSHNELL, a citizen of the United States, residing at Cold Springs, county of Putnam, and State 5 of New York, have invented certain new and useful Improvements in Car-Axle Mountings, fully described and represented in the following specification and the accompanying drawings, forming a part of the 10 same.

The present invention relates to a mounting for car-axle boxes upon the bodies of small cars like mine-cars; and the object of the invention is to furnish a means, without 15 any complicated attachments, of rendering the two boxes upon each axle self-aligning and to hold them firmly in such aligned position, preferably by the same means that secures them to the bottom or frame of the 20 car. Such self-alignment is obtained by providing clearance between the axle-boxes and the parts which hold them upon the car-body.

Means is provided for securing the boxes 25 firmly at a suitable distance apart to hold the axle from end-play, and to rigidly resist any thrust along the axle.

The thrust in the direction of travel is resisted by simple lugs cast upon the axle-boxes, operating with a channel tie-bar which holds the boxes upon the car-body. 30

These objects are attained by extending the channel bar across the bottom of the car-body with the flanges projected downwardly, and notching the flanges near the 35 ends of the bar to fit loosely wings formed integral with the axle-boxes.

This connects both of the axle-boxes firmly to the same channel-bar, and clearance is provided upon the boxes to permit 40 their self-alignment in every direction, to the small extent that is necessary, while affording a rigid connection of the parts.

The invention will be understood by reference to the annexed drawing, in which Figure 1 is an elevation of one pair of wheels with their complete mounting upon a car-bottom; Fig. 2 is a cross-section of the parts shown in Fig. 1 taken on line 45 2-2 in Fig. 4; Fig. 3 is a perspective view showing a car-axle with the boxes thereon, and a part of the channel-bar engaged with one of the boxes which is nearly concealed;

Fig. 4 shows the upper side of one of the axle-boxes with the portion of the axle 55 which extends through the same, and a horizontal section of the channel-flanges at the ends of the lugs *f*; and Fig. 5 is a side elevation of the parts in connection with one of the axle-boxes. 60

Figs. 2 to 5 inclusive are upon a scale three times as great as Fig. 1.

A designates the body of the car, or a bolster extended across the same. *A* channel bar *a*, *a'* is secured to the bottom of the 65 car by bolts *l*. *B* designates the axle, with wheels *C* upon its ends. The body *D* of the axle-boxes is shown fitted with clearance, between the flanges *a'*, which project downwardly from the web *a* of the channel-bar. 70

The channel-bar is extended across the bottom of the car-body immediately above the axle, and its flanges notched at *c* at the sides of each box. The bolts *l* pass through holes *l'* in the web, with clearance to permit 75 the required adjustment.

The axle-boxes are cast of a single piece with a wing *d* upon each side, adapted to fit into and loosely engage the notch *c* in the channel-flange, to resist end-thrust. The 80 axle-box has also a lug *f* projected from each side toward the inner side of the channel-flange to engage the same loosely, so that it may resist side-thrust upon the axle.

Bolt-holes *g* are extended through the 85 channels adjacent to the notches *c*, and corresponding bolt-holes *e* are extended vertically through the wings into recesses *h* upon the under sides of the wings. Bolts *j* are extended through the holes in the channel 90 and wings, and nuts *i* applied thereto serve to clamp the boxes to the channel in their working position; the axle operating to align the boxes perfectly by reasons of the provisions for self-adjustment of the boxes. 95 The bolts *j* extend upward through the car bottom, to facilitate the tightening of the bolts when they work loose by wear. The chief purpose of the bolts *j* is to hold the journal-boxes to the car if turned over or 100 thrown off of the track, and they do not prevent the self-alignment of the boxes at all times.

The tops of the wings are made convex or arched transversely of the axle and bear 105 directly upon the under side of the channel-

web *a*, and either or both of the holes *e* and *g* is made with clearance around the bolts *j* so that the axle-box may rock upon the web of the channel, to aline the boxes with the axle when mounted upon the channel-bar.

The notches in the channel-flanges are made sufficiently wider than the wings *d* to permit the self-adjustment of the boxes 10 in a horizontal plane, to compensate for any lack of alinement between the channel-bar and the working position of the axle.

It will thus be seen that the clearance between the sides of the wings and the notches 15 *d* permits adjustment in a horizontal plane, while the clearance between the ends of the lugs *f* and the interior of the channel-flanges *a'* (see Fig. 4) permits lateral adjustment of the boxes upon the channel, and the 20 arched tops of the wings permit the adjustment of the boxes in a vertical plane; while the securing of the boxes with all these compensations is provided by the bolts *j*, which clamp the boxes to the channel, and 25 to the bottom of the car, if desired.

The clearance provided adjacent to the adjustable parts may be made of any magnitude to provide an adequate self-alinement for these parts.

30 Fig. 2 shows the rolls within the bore of the box which, in practice, are retained therein by a cap forced into the end of the bore. The cap therefore requires no bolting as in other constructions.

35 Since the box is composed of a single simple casting and requires merely boring out and facing at the end which takes the thrust, its cost is very small compared with that of boxes of more complicated character.

40 The only work required for mounting this channel-bar and boxes upon the car is to drill the holes for the bolts.

The employment of the wings and lugs 45 to transmit thrust, combined with the arched top, gives great strength to the box for the amount of metal employed, while the distance from the center of the axle from the car-bottom is reduced to the minimum, which is a point of great importance.

50 The advantages of this construction may be summed up as follows:

First, that it permits adjustment in a horizontal plane—

55 Second, that it permits lateral adjustment of the boxes upon the channel—

Third, that the arched top to the wings permits the adjustment of the boxes in a vertical plane—

60 Fourth, that the clearance provided adjacent to the adjustable part may be made of any magnitude desired.

The snug fitting of car axle-boxes between the flanges of a channel-bar does not 65 afford the self-adjustment of the boxes to

the axle which is secured by my construction, and such snug fitting is not claimed herein, as the essential feature of my invention is the mounting of the boxes upon a channel-bar between the flanges, and providing means upon the boxes to engage the flanges longitudinally and laterally with clearance for self-adjustment of the boxes between the flanges. The precise form of the parts is not therefore essential, but the channel-bar may be made of a casting instead of wrought-metal as shown, and the means of engaging the boxes with the flanges may be varied without departing from the invention if the clearance be provided to afford the self-adjustment described.

Having thus set forth the nature of the invention what is claimed herein is:

1. The combination, with the floor of a mining or similar car, of a channel-bar secured transversely beneath the car-body with the flanges projected downwardly, and axle-boxes fitted between the flanges near the opposite ends of the channel, and provided with means to engage the flanges longitudinally and laterally thereof with clearance for self-adjustment of the boxes between the flanges.

2. A car-axle mounting, comprising a channel-bar with transverse notches near its ends and axle-boxes having projections adapted to fit said notches and held thereby against end-thrust.

3. A car-axle mounting, comprising a channel-bar with transverse notches in its flanges near their ends, and axle-boxes fitted between the flanges and having wings adapted to fit the said notches and arched upon the side next to the channel-bar to bear adjustably thereon.

4. A car-axle mounting, comprising a channel-bar with transverse notches in its flanges near their ends, and axle-boxes having wings fitted with clearance to the said notches and arched upon the side next to the channel-bar, whereby the box is permitted adjustment in both horizontal and vertical planes.

5. A car-axle mounting, comprising a channel-bar with transverse notches in its flanges near their ends, and bolt-holes in its web next the notches, and axle-boxes having wings fitted to the said notches, and bolts extended through the wings and channel-web and the floor of the car, thus connecting all the parts by the same bolts.

6. A car-axle mounting, comprising a channel-bar with transverse notches in its flanges near their ends and bolt-holes in its web next the notches, axle-boxes having wings fitted to the said notches and arched upon the side next to the channel-bar, and the ends of the wings being recessed upon the under side and provided with bolt-holes.

corresponding to the bolt-holes in the channel-web, for the insertion of bolts to secure the boxes adjustably upon the web.

7. A car-axle mounting, comprising a channel-bar with transverse notches in its flanges near their ends, an axle having boxes fitted between the said flanges and having wings fitted to the notches, lugs projected

from the boxes at opposite sides of the wings and fitted to the inner sides of the flanges, ¹⁰ and bolts extended through the wings and clamping the boxes to the channel-bar when adjusted in line with the axle.

In testimony whereof I have hereunto set my hand.

JAMES E. BUSHNELL.
